UNITED STATES PATENT OFFICE.

RICHARD H. GOLDSBOROUGH, OF WASHINGTON, DISTRICT OF COLUMBIA.

TORPEDO-LAUNCHING APPARATUS.

1,245,334.

Specification of Letters Patent. Patented Nov. 6, 1917.

Application filed April 30, 1915. Serial No. 24,948.

To all whom it may concern:

Be it known that I, RICHARD H. GOLDSBOROUGH, a citizen of the United States, residing at Washington, in the District of Columbia, have invented or discovered certain new and useful Improvements in Torpedo-Launching Apparatus, of which the following is a specification, reference being had therein to the accompanying drawings.

10. This invention relates to mechanism applicable to submarine boats and other offensive or defensive vessels or structures for handling and directing torpedoes and the like, and has for its general object the provision of improved means whereby such torpedoes may be conveniently and safely placed in discharging position, accurately aimed or directed in accordance with the distance and bearing of the target, and discharged, said means being adapted to permit the discharge of a torpedo in any direction through a wide arc so as accurately to reach its desired target irrespective of the relative positions of said target and the vessel or other structure from which said torpedo is discharged.

The foregoing and other objects of the invention, together with means whereby the same may be carried into effect, will best be understood from the following description of one form or embodiment thereof illustrated in the accompanying drawings. It will be understood, however, that the particular construction described and shown has been chosen for illustrative purposes merely, and that the invention, as defined by the claims hereunto appended, may be otherwise practised without departing from the spirit and scope thereof.

40. In said drawings:

Figure 1 is a vertical sectional view, partly in elevation and partly broken away, of one complete unit of the apparatus as applied to a submarine vessel.

45. Fig. 2 is a vertical section of one of the periscopes of said vessel and associated parts constituting a portion of the alti-scopic sighting and aiming or directing mechanism.

50. Figs. 3, 4, 5 and 6 are enlarged horizontal sections on the lines 3-3, 4-4, 5-5 and 6-6, respectively, Fig. 2.

Fig. 7 is a partial transverse vertical section of the torpedo turret or cradle.

55. Fig. 8 is a fragmentary vertical section,

on a somewhat reduced scale, of certain parts shown at the bottom of Fig. 1, illustrating these parts in a different position.

Fig. 9 is a detail vertical sectional view of the means for expelling a torpedo from 60 the loading lock and placing the same in position in the turret or cradle.

Fig. 10 is a detail plan view of the graduated arc upon which the adjustment of the directing mechanism is indicated. 65

Fig. 11 is a diagrammatic plan view of a complete submarine or other vessel equipped with four units of the apparatus.

Referring to Fig. 1, 15 denotes the bottom of a submarine or other vessel having a keel 70 16, and 17 an interior deck or floor.

18 (see also Figs. 7, 8, 9 and 11) denotes torpedoes each provided with the usual propellers 19 and firing head 20.

Said torpedoes are directed by and discharged from a rotary or dirigible turret 75 or cradle 21 having a torpedo tube 22 preferably provided at its lower side with suitable rollers 23 to facilitate the introduction of torpedoes thereinto and their discharge 80 therefrom. As shown said turret or cradle is of a flat cylindrical form with its upper and lower plane faces arranged substantially horizontally, the tube 22 being also substantially horizontal and extending diametrically through said turret from side to side. The turret or cradle 21 is carried by a vertical stem or shaft 23 extending upwardly from the center of the upper face thereof and by means of which said turret 85 or cradle may be turned on a vertical axis and raised or lowered into and out of a suitably formed chamber or housing 24 formed in the bottom of the vessel and open to the water. The stem or shaft 23 extends 90 upwardly through a suitably packed bearing 25 in the top of the chamber 24, said stem being rotatable and longitudinally movable in said bearing by mechanism hereinafter described. 95

The torpedoes are deposited in the torpedo tube 22, when the turret or cradle 21 is raised into loading position in the chamber 24, as shown in Fig. 8, through a cylindrical loading chamber or lock 27 provided 100

with annular packings 28 adapted to engage a torpedo in said lock and make a substantially water-tight joint therewith. The lock 27 is adapted to be closed at its inner and outer ends respectively by sliding gates 29 110

and 30 operated by levers 31 and 32 pivoted to a bracket 33 secured to the top of the lock 27. Said levers are actuated and controlled respectively, by cam grooves in a double-faced 5 path cam 34 journaled in the bracket 33 and operatively connected, as by a sprocket chain 35, with a hand wheel or other actuator 36. The arrangement of the grooves in the cam 34 is such that, as said cam is turned from the 10 position shown in Fig. 1, the outer gate 30 will first be opened, will be held open while the inner gate is closed, and will be again closed before said gate 29 is opened. The gate 29 carries a fitting 37 (see Fig. 9) provided with an inwardly closing check valve 38 which coöperates with the end of a sleeve or tube 40 provided with annular packings 39 adapted to form a water tight joint with an expelling rod 41 arranged to slide longitudinally in said sleeve or tube.

In the operation of loading the torpedo tube 22 the turret or cradle 21 is raised, by mechanism hereinafter described, into the position shown in Fig. 8 and the cam 34 turned to close the outer gate 30 and open the inner gate 29 as shown in Fig. 1. The forward end of the torpedo 18 is then inserted into the lock 27, as shown in Fig. 1, said torpedo forming substantially water-tight 25 joints with the wall of said lock through the packing rings 28. The cam 34 is then turned a sufficient distance to open the outer gate 30 and the torpedo moved inwardly through the lock and partly into the torpedo 30 tube 22 into the position shown in Fig. 8. The cam 34 is then further turned to close the inner gate 29. The expelling rod 41 is thereafter inserted through the sleeve 39, opening the valve 38 and by engagement 40 with the end of the propeller shaft of the 45 torpedo 18, moving said torpedo out of the lock 27 and entirely into the torpedo tube 22.

The torpedo tube is preferably of somewhat less length than the torpedoes it is intended to accommodate, the chamber or housing 24 being formed with an extension 43 to receive the forward end of a torpedo in said torpedo tube when the turret or cradle 21 is in its raised position in said chamber or 50 housing 24.

42 (see Fig. 1) denotes an arm pivoted at one end to a bracket 44 on the lock 27 and engaged at its opposite end by a projection or head 45 on the outer gate 30 when the latter is closed. 46 denotes a spring surrounding a rod 47 carried by the arm 42 and interposed between a head on said rod and a bracket 48 on the lock 27, said spring acting normally to raise the arm 42 when disengaged by the head 45 when the gate 30 is open. 49 denotes a stop pin carried by the arm 42 and sliding in a suitably packed opening in the wall of the lock 27. When the gate 30 is closed and the end of the arm 65 42 engaged by the head 45, as shown in

Fig. 1, the end of the stop pin 49 is projected inwardly into the interior of the lock chamber and into a position to engage one side of the head of a torpedo inserted into said chamber and prevent the same from being moved forwardly a sufficient distance to cause the firing pin 20 thereof to engage the gate 30 and accidentally explode said torpedo. When the gate 30 is open the spring 46 raises the stop pin 49, thereby permitting said torpedo to be moved into the torpedo tube 22 as above explained.

For a similar purpose stop lugs 50 are provided on the walls of the extension 43, said stop lugs being adapted by engagement with the sides of the head of the torpedo to prevent the firing pin 20 from being brought into engagement with the end wall of said extension.

Referring to Figs. 1 to 6, the periscope or altoscopic sighting and aiming device comprises a rigid vertical casing 51 inclosing the altiscope proper 52. Said altiscope 52 is mounted on trunnions 53 within said casing 51 the interior of which is of a suitable form to permit a limiting swinging movement of said altiscope proper upon said trunnions. 54 denotes a micrometer carried by the casing 51 and connected with the altiscope 52 adjacent its lower end, whereby said altiscope may be adjusted on its trunnions 53 and the adjustment indicated.

The particular construction of the altiscope proper 52 is susceptible of considerable variation. Essentially said altiscope comprises an upright tube provided near its base with an ocular 55 into which the image of a target will be reflected by means of prisms 56 and 57, the image of the target entering the altiscope at the receiver 58 and thence being reflected downward through the prisms to the ocular, the line of collimation of the receiver or objective portion 58 forming an angle of 90° with that of the vertical portion of the altiscope, the reflecting surface of the prism 56 being arranged at an angle of 45° to both. As herein shown the vertical tube of the altiscope is provided with an objective lense 60 and with one or more reversing lenses 61, while the ocular 55 is provided with a suitable lense 62, the whole constituting a multiple inversion telescope. 59 denotes a plain glass disk or zone plate located in the upper focal plane of the instrument, that is to say the 110 focal plane of the objective lense 60. Said zone plate is for the purpose of assisting in determining ranges and speeds of travel of moving targets but is not shown nor described in detail herein as it forms no part 115 of the present invention, being covered by the claims of another application filed by me March 20, 1915, Serial No. 15,843.

63 denotes the cross hairs for determining the line of sight of the instrument, said cross 120 hairs being located in the upper focal plane of the objective lense 60. Said zone plate 125 is for the purpose of assisting in determining ranges and speeds of travel of moving targets but is not shown nor described in detail herein as it forms no part of the present invention, being covered by the claims of another application filed by me March 20, 1915, Serial No. 15,843.

63 denotes the cross hairs for determining the line of sight of the instrument, said cross 130

hairs being located in a lower focal plane, that is to say in the focal plane of one of the lenses 61. 64 denotes means, accessible from outside the casing 51, for adjusting the cross hairs 63 in order to compensate for refraction or to apply other necessary corrections. The adjustment of the altiscope 52 on its trunnions 53 enables the same to be properly sighted upon the target irrespective of the distance of the latter, and the measurement of said adjustment by means of the micrometer 54 enables the distance or range of said target to be established in accordance with the principles more fully explained in my prior application No. 15,843, above referred to. For the purposes of the present specification these principles may be briefly explained as follows.

In the case of a submarine vessel, for example, the vessel being on an even keel, as shown by the leveling devices with which said vessel is or may be equipped, and the depth of submersion being shown by the pressure gages, the altiscope is sighted, by means of its horizontal cross hair, upon the target at the water line. Preferably, although not necessarily, the depth of submersion will be such as to bring the water line at the level of the trunnions 53. A vertical right triangle is thus formed, of which the two legs are the axis of the altiscope above the water line and the line of sight from the objective to the target, respectively, while the hypotenuse is the horizontal line from the altiscope to the target. The length of the shorter leg (namely, the height of the altiscope from the water line to the center of the reflecting surface of the upper prism 56) being known, and the angle included between said leg and the hypotenuse being measured by the micrometer 54, the length of said hypotenuse, which is the desired range, may readily be determined by a well known trigonometric formula.

The altiscope casing 51 extends upwardly through the upper deck of the vessel (not shown) in a manner similar to the periscopes now in common use, and is closed at its upper end by a cap 65 provided with a glazed opening 66 opposite the objective or receiver 58 of the altiscope proper 52. Said casing is supported at its lower end by a base 67, preferably formed integral therewith and provided at its bottom with a substantially circular platform 68 provided with rollers 69 which run on a circular track 70 carried by the deck or floor 17, the whole constituting a turn-table upon which said altiscope casing may be turned on its vertical axis. 71 denotes a vertical sleeve or cylindrical journal extending upwardly from said floor or deck 17 and supporting the base 67 of the altiscope casing through the medium of a ball or roller bearing 72.

The altiscope casing is operatively con-

nected with the torpedo turret or cradle 21 in such a manner that when the altiscope is turned on its vertical axis to sight the same upon any desired target the torpedo tube will be properly aimed at said target. To this end the following construction is provided...

The shaft or stem 23 by which the torpedo turret or cradle is supported is formed hollow to receive the lower end of a spindle 73 which extends downwardly from the altiscope casing 51 in alignment therewith, and within the sleeve 71. Said spindle 73 is provided for a limited distance at its upper end with longitudinal grooves 74 which receive 80 interior splines or feathers 75 at the upper end of the stem or hollow shaft 23. The construction is such that said stem or shaft 23 is guided for vertical movement on the spindle 73, so as to telescope therewith, said movement being limited by the length of the grooves 74, and is connected with said spindle for rotation therewith in all positions.

For vertically moving the stem or hollow shaft 23 in order to raise and lower the torpedo turret or cradle into loading and discharging positions, respectively, said shaft or stem is provided with a series of annular flanges 76 constituting rack teeth adapted, 95 in all angular positions of said stem or shaft, to mesh with pinions 77 carried by shafts 78 journaled in brackets 79 supported on a suitable platform or floor 80 within the vessel. Each of the shafts 78 carries one 100 of a pair of intermeshing gears 81, one of which is operatively connected, through suitable gearing, with a suitable actuator, herein shown as an electric motor 82. Said electric motor is energized from any suitable source of electric power, herein shown as a battery 83 connected with said motor through suitable wiring 84, and is controlled by means of a suitable button or switch 85 arranged within convenient reach of an 110 operator on the platform 68.

For simultaneously turning the altiscope and cradle upon a vertical axis in order to sight the target and aim the torpedo tube the following mechanism is provided. 86 denotes a horizontally disposed worm wheel journaled and supported at its lower side upon the bearing 25 and at its upper side in a bracket 87 carried on the top of the chamber or housing 24. Said worm wheel 86 is 115 splined to the stem 23 in such a manner as to rotate therewith while permitting longitudinal movement of said stem. 88 denotes a worm co-operating with the worm wheel 86 and connected by gears 89 with any suitable actuator, herein shown as an electric motor 90 supplied with current through suitable wires 91 from the battery 83 and controlled by a button or switch 92 also arranged in convenient position adjacent 120

the platform 68. In order to indicate the position of the altiscope and cradle the altiscope casing base 67, as herein shown, is provided with a suitable pointer or indicator 93 which co-operates with a graduated arc 94 suitably supported independently of the altiscope, as by a bracket 95 raising from the floor or deck 17.

In operation, a torpedo having been deposited in the torpedo tube 22, as heretofore explained, the switch or button 85 is operated to cause the cradle 21 to be lowered into discharging position as shown in full lines in Fig. 1. The switch or button 92 is then operated to cause the altiscope and cradle to be turned until the desired target is brought into the field of view and in alinement with the vertical cross hair, thereby causing the axis of the torpedo tube 22 to be aimed at or directed toward said target. The micrometer 54 may then be operated to turn the altiscope proper 52 upon its trunnions 53 in order to bring said target into alinement with the horizontal cross hair of the instrument, the adjustment of said micrometer indicating the angle formed by the altiscope with the horizontal, from which angle the range of the target may be determined, as above explained. The range of said target, and, in the case of a moving target, its speed of travel, having been determined by these or any other means, suitable correction may, if necessary, be applied by turning the altiscope and cradle the necessary amount, such re-adjustment being conveniently indicated upon the graduated arc 94. When properly directed the torpedo may be discharged by any suitable means. Such means are herein diagrammatically indicated by the wires 96 leading from the battery 83 through a suitable opening in the stem 23, said wires carrying at their lower ends contact members 97 which co-operate with suitable contact members 98 on the torpedo and electrically connected with suitable starting mechanism therein. The electric circuit provided by the wires 96 includes a suitable button or switch 99, also arranged in convenient position adjacent the platform 68, whereby the torpedo, when properly directed, may be discharged at will.

In Fig. 11 is diagrammatically illustrated a vessel provided with a torpedo battery comprising four units of the character above described in detail. Each of said units comprises a torpedo turret or cradle 21 and associated parts including an altiscope by which it is operated and controlled, two of said turrets, as shown, being located at each side of the keel 16. It will be seen that each turret has an effective range or sweep through a horizontal angle of approximately 166°, being limited only by the position of the keel 16 and the next adjacent turret; so that, by providing a suitable number of units, it

will be seen that a torpedo can, at any time, be discharged in practically any direction irrespective of the position of the vessel. Preferably each arc 94 will be so graduated as to indicate the possible sweep of the corresponding turret so as to prevent accidental discharge of a torpedo at any improper or dangerous angle. In Fig. 11 is also diagrammatically illustrated a pair of torpedo racks or carriers, 100, whereby the torpedoes 75 may be conveniently presented to the locks 27 for the insertion therethrough into the torpedo tubes.

Having thus described my invention I claim and desire to secure by Letters Patent:

1. A structure of the character described provided with a torpedo tube, means within said structure for loading said torpedo tube, and means for supporting said tube adapted to permit the same to be moved from a position adjacent said loading means into discharging position exterior to said structure.

2. A war vessel provided in its bottom with a chamber or housing open to the water, a torpedo tube, and means for supporting said torpedo tube adapted to permit the same to be raised and lowered into and out of said chamber or housing.

3. A war vessel provided in its bottom with a chamber or housing open to the water, a torpedo tube, means adjacent said chamber or housing for loading said torpedo tube, and means for supporting said torpedo tube adapted to permit the same to be raised and lowered into and out of said chamber or housing.

4. In a structure of the character described, a dirigible torpedo tube, sighting means therefor, and means for supporting said tube adapted to permit the same to be moved by said sighting means and to be moved relatively to said sighting means into and out of discharging position.

5. In a structure of the character described, a vertically movable turret or cradle provided with a torpedo tube, a rotatable stem by which said turret or cradle is carried, a rotatable but vertically stationary altiscope for sighting said torpedo tube, said altiscope having a spindle telescoping with said stem, and said spindle and stem being connected for rotation in unison.

6. A structure of the character described provided with a torpedo tube and a loading lock, said tube and lock being relatively movable into and out of axial alinement.

7. In a structure of the character described, a torpedo tube exterior to said structure, a loading lock within said structure and communicating with said tube, and gates for closing the opposite ends of said lock.

8. In a structure of the character de-

scribed, a torpedo tube exterior to said structure, a loading lock within said structure and communicating with the exterior thereof, gates for closing the opposite ends of said lock, and means for supporting said tube adapted to permit the same to be moved into and out of axial alinement with said lock.

9. In a structure of the character described, a torpedo tube, a loading lock communicating therewith, gates for closing the opposite ends of said lock, and common operating mechanism for said gates.

10. In a structure of the character described, a torpedo tube, a loading lock communicating therewith, gates for closing the opposite ends of said lock, levers for operating said gates and a double-faced cam having grooves for operating said levers respectively.

11. The combination with a torpedo tube, a loading lock communicating therewith, and a gate for controlling such communication, of an arm pivoted to said lock, a stop pin carried by said arm and passing through the wall of said lock, a spring coöperating with said arm for withdrawing said pin from the interior of said lock, and a projection on said gate coöperating with said arm to move said pin into said lock.

12. The combination with a torpedo tube and loading means therefor, of a chamber or housing for said torpedo tube, and a stop in said chamber for limiting the movement of a torpedo inserted into said tube.

13. The combination with a torpedo tube and a loading lock communicating therewith, of a gate for closing the inner end of said lock, and an expelling rod passing through said gate for moving a torpedo from said lock into said tube.

14. The combination with a torpedo tube and a loading lock communicating therewith, of a gate for closing the inner end of said lock, a fitting carried by said gate and provided with a sleeve communicating with the interior of said lock, a valve in said fitting for controlling such communication, an expelling rod passing through said sleeve, and packing rings in said sleeve adapted to

make substantially water-tight joints with said rod.

15. A war vessel provided at its bottom with dirigible means for determining the course of a torpedo and sighting means operatively connected therewith for controlling the same and extending above said vessel.

16. A war vessel provided at its bottom with dirigible means for determining the course of a torpedo and sighting means operatively connected therewith for controlling the same and extending above said vessel, said sighting means being operable from the interior of said vessel.

17. A war vessel provided at its bottom with a dirigible torpedo tube mounted to turn on a substantially vertical axis and an altiscope connected with said torpedo tube, extending above said vessel, and mounted to turn on an axis coincident with said first-named axis.

18. In an apparatus of the character described, an altiscope having a hollow base provided with a platform, a floor or deck having an upright journal on which said base is rotatably mounted, a track on said floor or deck, and rollers carried by said platform and running on said track.

19. In a structure of the character described, in combination, a turret or cradle provided with a torpedo tube, a rotatable stem by which said turret or cradle is carried, an altiscope having a hollow base provided with a platform, a floor or deck having a hollow upright journal on which said base is rotatably mounted, a track on said floor or deck and rollers carried by said platform and running on said track, said altiscope having a spindle extending downwardly through said hollow journal and telescoping with said stem, and said spindle and stem being connected for rotation in unison.

In testimony whereof I affix my signature, in presence of two witnesses.

RICHARD H. GOLDSBOROUGH.
